US0D1017940S

(12) **United States Design Patent** (10) **Patent No.:** **US D1,017,940 S**
(45) **Date of Patent:** **** Mar. 12, 2024**

(54) **CLEANING DEVICE**

(71) Applicant: **Uproot Lint LLC**, Miami, FL (US)

(72) Inventor: **Mehul Patel**, Miami, FL (US)

(73) Assignee: **Uproot Lint LLC**, Miami, FL (US)

(**) Term: **15 Years**

(21) Appl. No.: **29/820,579**

(22) Filed: **Dec. 22, 2021**

(51) **LOC (14) Cl.** **07-05**

(52) **U.S. Cl.**

USPC **D32/46**; D4/118; D30/158; D30/159

(57) **CLAIM**

The ornamental design for a cleaning device, as shown and described.

DESCRIPTION

FIG. 1 is a perspective view of an embodiment of the cleaning device showing my new design;

FIG. 2 is a front plan view of the cleaning device of FIG. 1; FIG. 3 is a rear plan view of the cleaning device of FIG. 1; FIG. 4 is a left side view of the cleaning device of FIG. 1; FIG. 5 is a right side view of the cleaning device of FIG. 1; FIG. 6 is a top plan view of the cleaning device of FIG. 1; and,

FIG. 7 is a bottom plan view of the cleaning device of FIG. 1.

The features shown in broken lines depict environmental subject matter only and form no part of the claimed design.

1 Claim, 6 Drawing Sheets
